Nexsen Pruet, LLC(57) **CLAIM**

The ornamental design for a window frame connector lineal, as shown and described.

DESCRIPTION

FIG. 1 is a front perspective view of the window frame connector lineal, showing my design;

FIG. 2 is a front elevation view thereof;

FIG. 3 is a top view thereof;

FIG. 4 is a bottom view thereof;

FIG. 5 is a right side elevation view thereof; and,

FIG. 6 is a left side elevation view thereof.

The window frame connector lineal is shown with a symbolic break in its length. The appearance of any portion of the window frame connector lineal between the break lines forms no part of the claimed design.
